TRUSS SIDE FRAME

Gilbert D. Fish, Pelham, N. Y., assignor to Welded Steel Shapes, Inc., New York, N. Y., a corporation of Pennsylvania

Application October 6, 1944, Serial No. 557,404

13 Claims. (Cl. 105—206)

1

The present invention relates to a truss construction for railway car trucks such as that generally known as a truss side frame.

General objects of the invention are to provide a simple truss side frame having one or more joints each of which is characterized by members at least some of which are of box formation including web and flange plates which utilizes a minimum of material in the junction of the members thereof while assuring efficient unloading of stresses from one member to another with no indirection and in which the full strength of every member entering the junction is developed, and efficient obtainment of any balanced system of forces in the systems of flanges and webs, with such obtainment for the flange system and for the web systems being effectively assured substantially independently, which is adapted to commercial production and which has unusual strength and load-carrying characteristics.

A more specific object of the invention is the provision of a truss side frame having at least one joint characterized by a plurality of members brought together at a common junction with at least two thereof of box formation wherein a system of transverse structure, such as flange plates, are in a desired condition of equilibrium substantially independently of web plate structure thereof due to employment of diaphragm means constituting a triangular truss system effectively connecting all of the transverse structural elements together.

Another object of the invention is to provide a simple but unusually sturdy truss side frame joint of a plurality of members including transverse structural elements, such as flange plates, which eliminates any necessity for the employment of connecting structure through which stresses would be transferred from transverse structure of any of the members to that of others along indirect paths, e. g., large and bulky gusset plates, the joint being characterized by diaphragm means such as transverse plates joined along transverse lines of meeting to all junctures of transverse structures of the members and to any of the latter which have no junctures with similar structure of other members and providing rigid connections therebetween by the equivalent of a truss system of triangular pattern for sub-

2

stantially direct transfer of stresses between the transverse structural elements.

Still another object of the invention is the provision of a truss side frame which is of simple construction and easily fabricated and is of exceptional strength, being composed of box-section members for superior efficiency and stiffness and which is especially well adapted to resist bending moments and torsional moments which may be caused by loads applied in any direction.

A further object of the invention is to provide such a compact, relatively light weight and strong truss side frame in which junctions of the members include diaphragm means constituting triangular truss systems joined to and substantially directly connecting together all of the transverse structural elements of the frame members including all junctures thereof thereby producing at each of the junctions a joint system of the transverse structural elements in equilibrium which may act in efficient stress transfer substantially independently of web systems.

A still further object of the invention is to provide structural embodiments of such truss side frame which are readily constructed by welding operations and which allow efficient use and operation thereof.

Other objects of the invention will in part be obvious and will in part appear hereinafter.

The invention accordingly comprises the features of construction, combination of elements and arrangement of parts, which will be exemplified in the constructions hereinafter set forth and the scope of the invention will be indicated in the claims.

For a fuller understanding of the nature and objects of the invention reference should be had to the following detailed description taken in connection with the accompanying drawings, in which:

Fig. 1 is a side elevational view, with parts broken away and in section, of an embodiment of the truss side frame of the present invention;

Fig. 2 is a sectional view taken on line 2—2 of Fig. 1, with some parts broken away;

Fig. 3 is a bottom plan view of the structure shown in Figs. 1 and 2, and with parts broken away to show certain internal structure of the tension member;

3

Figs. 4, 5 and 6 are sectional views respectively taken on lines 4—4, 5—5 and 6—6 of Fig. 1;

Fig. 7 is a vertical section to an enlarged scale of an end of the truss side frame shown in Fig. 1;

Fig. 8 is a side elevational view, with parts broken away, of one embodiment of truss joint of the present invention employable in the truss side frame shown in Fig. 1;

Fig. 9 is an end elevational view of the structure shown in Fig. 8;

Fig. 10 is a side elevational view of the flange plate system of the structure shown in Fig. 8;

Fig. 11 is a side elevational view of a web plate system of the structure shown in Fig. 8; and

Fig. 12 is a vertical section of a modified form of the structure shown in Fig. 8.

Truss members of box formation, i. e. box-section members, are especially advantageous for structural members which have to resist forces in various directions, which cause bending about more than one axis and/or cause torsion. A truss structure composed of box-section members is superior in efficiency and stiffness to one composed of the more familiar sections, such as angles, I-beams, channels, T's or other open sections, if some or all of its principal members are subject to considerable bending about more than one axis, or to considerable torsion. Truss members of box formation have been employed only infrequently in truss structures, perhaps because their closed form has presented many difficulties in connecting them one to another in such manner as to form joints capable of developing all the strength or even most of the strength of the members. In riveted or bolted truss construction, satisfactory joints involving two, three or more meeting ends of box-section members are not feasible. In foundry practice, a cast metal joint in box members cannot be produced in such form as to develop the strength of all sides of the members.

In a truss structure, a joint is formed wherever two or more members meet. Three and four are the most usual number of members forming a joint, any member which runs completely through a joint and which extends to other joints on both sides being recognized as two members. At end supports of a truss structure two members frequently form the joint; and five or even more members sometimes form a truss joint. At any joint, by the laws of mechanics, a system of forces and moments in equilibrium is at every instant formed by (a) the forces and moments transmitted to the joint by all the members meeting, and (b) the forces and moments comprising any external loads applied to the truss at that joint. The joint must therefore be capable of transmitting the forces and moments from each member to the other members and of transmitting any external loads to the members. The forces and moments above referred to may act in any direction, subject to the requirement of equilibrium of the entire system.

In the following description and claims the terms "webs" and "web plates" are employed in their usual sense to identify those parts or plates of the box-section members which are arranged in or constitute the opposite faces lying in two planes parallel to the face of the drawings and for convenience may be considered to be vertical and to extend north and south. The remaining parts or plates in the two opposed faces of each member which are arranged substantially at right angles to the face of the drawings and the web plates and which extend transversely

4

between pairs of the latter are herein identified as "flanges" and "flange plates." It is to be understood that "plate" broadly identifies parts in either the flange system or web systems which may be made as separate pieces and then welded along edges thereof to parts in the other of those systems or integral with the latter parts such as by bending a flat plate into an angle to form a web and attached flange or into a channel to form one flange and two webs or two flanges and one web.

In order fully to develop the strength of the members by known means, such as gusset plates commonly employed in conventional truss design, such gussets arranged in face engagement with web structure and welded to the members must extend far enough along the members to permit the flange plates to transfer their stresses by longitudinal shear through their edges, without unduly high intensity of longitudinal shearing stress. Generally speaking, the gussets must extend along the edge of each flange plate a distance equal to or exceeding the flange plate width, to develop the full tensile or compressive strength of the flange plate. Further, the gussets must be thick enough to withstand the stresses to be transmitted indirectly through them. These requirements cause the formation of bulky joints which necessitate the use of far too much material. The present invention eliminates these and other difficulties of prior art practices.

The purposes of a truss joint are effectively accomplished in accordance with the present invention which permits a desired employment of box-section members in a truss side frame embodiment such as that shown in Figs. 1 to 7 inclusive, in which like numerals refer to like parts throughout.

The truss side frame structure 10, which is designed for employment in railway car trucks, shown in Figs. 1 to 7 inclusive, comprises a longitudinal compression member 11 terminating at both ends in wheel connecting means 12, 12 and a tension member 13 joined to the compression member 11 at each end thereof in the vicinity of the wheel connecting means 12, 12. The tension member 13 is, in truss terminology, three distinct members, namely a bolster spring seat section 14 and a pair of flanking oblique sections 15, 15. As is usual, the truss side frame 10 also includes a pair of laterally spaced apart vertical bolster guide column members 16, 16 joined to and extending between the compression member 11 and the tension member 13, to define a bolster receiving space 17, with the junctions to the tension member being in the vicinity of the junctions of the oblique sections 15, 15 with the bolster spring seat section 14. The guide column members 16, 16 are provided with bolster guide plates 18, 18 for vertical guidance of a railway car bolster which is to be positioned therebetween in space 17 and supported upon suitable spring structure seated on the spring seat section 14 in any suitable manner, such as by positioning helical spring structure down over projecting lugs 19—19.

It will be noted that each of the compression, tension and guide column members 11, 13 and 16, 16 are box-section members, i. e. of box formation, each comprising a pair of spaced apart transversely extending flange plates and a pair of spaced apart web plates joined thereto, preferably by welding. As is evident from Figs. 1 and 4, the compression member 11 may comprise a U-shaped element or channel providing an exterior flange plate 20 and two opposed web plates

21, 21 and an interior flange plate 22 formed of five pieces of plate stock consisting of two end pieces 23, 23 each extending from an end of the frame to a guide column member 16, a midsection piece 24 extending between the two guide column members 16, 16 and two spanner pieces 25, 25 each of which is aligned with and bridges across between the flange plate pieces 23 and 24. This construction permits the ends of the flange plate pieces 23, 23 and 24 to be turned inwardly and welded to the flange plate 20 to provide internal connecting plates 26—26 above the ends of the guide column members 16, 16 and preferably aligned with transverse elements or flanges thereof.

The box-section tension member 13 has each of its oblique sections 15 comprised of an interior flange plate 27, an exterior flange plate 28 and a pair of web plates 29, 29. The bolster spring seat section 14 comprises an interior flange plate 30, an exterior flange plate 31 and a pair of web plates 32, 32. Preferably, for simplification in fabrication, the interior flange plates 27, 27 and 30 are made integral from a single piece of plate stock and the exterior flange plates 28, 28 and 31 are similarly formed from a single piece, in each case bent to proper shape.

Flange plate 30 of the bolster spring seat section 14 is preferably made wider than the tension member 13 to provide a platform to support the bolster springs which are to be held in position by lugs 19—19 carried by flange plate 30. The platform provided by the flange plate 30 preferably has its overhanging edges supported by brackets 33—33 welded to the web plates 32, 32.

Since it is desired to insure maximum strength in the bolster spring seat section 14, preferably reinforcing ribs 34—34 are provided internally thereof and are suitably anchored to webs such as by welding at 35—35. For a similar reason, the web plates 32, 32 are made from thicker stock than are the web plates 29—29, and these are joined together by cutting their meeting edges to fit along lines 36, 36 and butt welding them to each other. Of course it will be understood that, if desired, the web plates on either side of the tension member 13 may be made integral by cutting them out of a single piece of plate stock.

The bolster guide column members 16, 16 may each comprise a U-shaped element providing a flange plate 37 and two web plates 38, 38, as will be seen in Fig. 5. Another flange plate 39 welded to the web plates 38, 38 completes the box structure thereof. The guide column members 16, 16 are positioned between the compression member 11 and the tension member 13 with the top end of each having its transverse flanges 37 and 39 substantially aligned with the plates 26, 26 and respectively welded to the flange plate pieces 24 and 23. The bottom end of each guide column member 16 is joined to the tension member 13 by welding at the junction of the seat section 14 with one of the oblique sections 15, such as at 49, preferably with the flange plate 37 meeting the interior flange plate of the tension member substantially at the juncture of the interior flange plates 27 and 30. The web plates 38—38 of the guide column members 16, 16 are substantially aligned with web plates 29—29 and 32, 32; but it is to be understood that web plates 38—38 may, if desired, be made integral with the web plates 29—29 and/or 32, 32, such as, for example, by cutting all of the web plates of the tension member 13 and the two guide column members 16, 16

on one side of the frame from a single piece of plate stock. For this purpose, of course, the inner face of the web plate structure will be made to overlap the edges of the flange plates of the members in lieu of the reverse as proposed in Fig. 1.

It will thus be noted that all of the previously identified members of the truss side frame are of box formation each comprising a pair of flange plates and a pair of web plates welded together or otherwise joined, such as by making certain of such elements integral with certain others thereof as previously proposed, along their lines of meeting as is shown in the drawings.

15 The most important joints or points of junction in the described frame are at the two junctions of the tension member 13 with the compression member 11 at the two ends of the frame, and at each of the junctions 40, 40 of the oblique sections 15, 15 with the seat section 14 of the tension member. The guide column members 16, 16 are joined to the tension member 13 at these last-named junctions, and in order efficiently to employ box-section members for the construction of the truss side frame it is necessary to attain equilibrium in the system of flange plates substantially independently of the web plates at these joints. To accomplish this result at one of these junctions 40, provision is made in accordance with the present invention to tie together all of the flange plates at the joint by means of rigid diaphragm structure.

This may be accomplished in accordance with the present invention by welding a diaphragm plate 41 to the juncture at 42 of the interior flange plate 30 with the interior flange plate 27 and anchoring it, such as by welding, to the juncture at 43 of the exterior flange plate 31 with the exterior flange plate 28. An additional diaphragm plate 44 is welded to the juncture at 45 of the interior flange plate 27 with the flange plate 39 and to the juncture at 43. As a result, all of the flange plates at the joint under consideration are substantially directly connected by a triangular truss system comprising diaphragm plates 41 and 44 and an additional diaphragm plate 45 which has been made integral with the interior flange plates 27 and 30.

50 It will thus be seen that three members of box formation are connected together at each of the junctions 40 of the seat section with one of the two oblique sections 15, 15 of the tension member by a truss system of triangular pattern, more particularly a triangular pattern of diaphragm plates with the vertices of the triangular pattern connecting every juncture of the flange plates of the members to every other juncture thereof in a substantially direct manner. Although obviously it is preferred to employ flat diaphragm plates which extend in straight lines between the junctures, or diaphragm means, such as a solid block, connecting the three flange junctures and which entirely encompass lines of action therebetween; a similar result may be attained by curved plates of sufficient rigidity and directness to attain the desired stress transfer without failure of elements.

Considering the joint at the junction of an end of the compression member 11 with one of the oblique sections 15 of the tension member, it will be seen that similar provision is made for attainment of equilibrium in the flange system. The interior flange 23 of the compression member is welded to the interior flange 27 of the oblique section at 47 and a diaphragm plate 48 extends

from the juncture at 47 substantially to the end of the exterior flange plate 28 at 49 and is respectively connected thereto by welding. An additional diaphragm plate 50 is provided, preferably by extending interior flange plate 27 beyond the juncture at 47 to meet with the exterior flange plate 20 of the compression member at 51, where it is welded thereto. The inter-connection of the flange plates of the compression and tension members is completed by an obliquely arranged diaphragm plate 52 anchored by welding at 51 and 48. Diaphragm plates 48, 50 and 52 thus constitute a truss system of triangular pattern which connects all of the flange plates 20, 23, 27 and 28 together. A third member is joined to the compression and tension members at their junction for the purpose of providing a wheel connecting means. This third member preferably comprises a single flange plate 53 welded to the juncture at 49 and a pair of web plates 54, 54 joined to flange plate 53 and to the oblique section 15 such as by welding them to the flange plate 53 and to the exterior flange plate 28.

A lateral support plate 55 is provided, but forms no element of the truss system at the end of the frame, and merely constitutes a bearing plate preferably held in position by welding to the flange plate 53 and web plates 54, 54. The diaphragm plate 52 is preferably extended beyond the juncture at 49 to provide a cover element 56 also forming no part of the truss system. It may be further desired to provide a bracket 57 welded to the oblique section 15 to cooperate with the support plate 55 and provide therewith means to seat upon a journal box indicated in dot-dash lines 58 for a wheel axle of a railway car.

It will thus be seen that at least two members of box formation are joined together at each end of the frame 10 with the employment of a triangular truss system comprising diaphragm plates 48, 50 and 52, these truss members consisting of the oblique section 15 of the tension member 13 and the compression member 11, to which has been connected at their junction a third member formed by the vertical flange plate 53 and its associated web plates 54, 54; and that all of the flange plates of those three members are substantially directly connected by diaphragm means forming a truss system of triangular pattern.

It will be evident from Fig. 7 that the connection between the flange plates of a plurality of members need not be accomplished with exactitude, particularly since it has been found by test that a small degree of variation does not introduce trouble. The dot-dash lines in Fig. 7 substantially represent the true lines of action of the diaphragm plate 48, the exterior flange plate 28 and support flange plate 53, which, it will be noted, intersect at 59 at the juncture of those three elements, but that the point 59 does not precisely coincide with the point 49 of juncture between the exterior flange plate 28 and the obliquely arranged diaphragm plate 52. If such exactitude of coincidence had been accomplished, which was found to be unnecessary and somewhat impractical in the fabrication of the structure, the diaphragm plate 48 and the flange plate 53 would have extended along the dotted lines to juncture with the diaphragm plate 52 at the point 49 to have their lines of action coincide with the dotted lines and intersect with the line of action of the diaphragm plate 52 at the point 49. However, this slight variation which has been found to be practical in commercial pro-

duction provides substantially direct connection to junctures of flange plates and has been found in practice to satisfy the requirements of equilibrium for all practical purposes.

Thus the truss side frame shown in Figs. 1 to 7 inclusive incorporates two embodiments of the truss structure of the present invention, and the characteristics thereof and desired ends attained thereby will be better appreciated by a reference to Figs. 8 to 15 inclusive. With the employment of box-section members welded together at junctions to form joints characterizing the present invention, box-section members can be joined in a manner as to develop all of the strength, or as much of the strength as may be required of all of the sides of the members. At each such joint a complete, self-contained truss system of all of the flange plates and a substantially independent self-contained truss system of all of the web plates are provided. Although the flange plates and the web plates are joined together where they meet and thus do not divide the stresses as if they were entirely independent systems, the joint which characterizes the truss system of the present invention provides direct stress paths which permit every single plate to transfer its stress into the joint without substantial assistance from any other plate of the same member.

Fig. 8 shows a truss side frame joint at which three box members 114, 115 and 116, similar to members 14, 15 and 16 of Figs. 1 to 7 inclusive, meet. The side plates 129, 132 and 138 of the three members 115, 114 and 116 on either side thereof are coplanar as shown in Fig. 9 and can be cut out of a single plate or can be joined by cutting their ends to fit and welding them one to another. As previously indicated, these side plates are the web plates and transverse plates 127, 128, 130, 131, 137 and 139 which lie at right angles to the web plates are the flange plates. The web plates are adapted to resist axial stresses of compression or tension in the members and also shearing stresses in their own planes and the flange plates are adapted to resist such axial stresses and also shearing stresses in their own transverse planes. Both flanges and both webs of a member, acting together as a unit, are adapted to resist torsional moments about the axis of the member and bending moments about any axis perpendicular thereto, i. e. any transverse axis. The lines of action of stresses in planes parallel to the webs for the system of flange plates are illustrated by the dotted lines in Fig. 10 and those for either system of web plates are illustrated by the dotted lines in Fig. 11.

At the junction 140, each flange plate meets and is joined to one flange plate of one of the other members along a transverse line and this juncture may be formed by welding or, alternatively, a single transverse plate may be bent to provide two connected or joined flange plates, one for one member and the other for another member. Thus in the structure shown in Figs. 8 and 10 the six flange plates 127, 139, 137, 130, 131 and 128 may be formed from three strips of flange stock, one providing flange plates 127 and 139, a second providing flange plates 137 and 130, and the third providing flange plates 131 and 128.

If the joint at the junction 140 of the three members 114, 115 and 116 consisted only of the junctures of the two sets of web plates 132, 129 and 138 and of the pairs of flange plates 130 and 131, 127 and 128, and 137 and 139, there

would be adequate provision for developing the strength of all web plates but not for developing the strength of any of the flange plates except with respect to shearing stresses in their own planes.

By adding diaphragm means such as three diaphragm plates 141, 144 and 146 of adequate thickness to provide a truss system of triangular pattern, with vertices thereof connected to the junctures or transverse lines of meeting of the flange plates at 142, 143 and 145 in Fig. 10, a framework is formed by which any balanced system of forces (i. e. system in equilibrium) in all of the flange plates can be developed by the joint, substantially independently of the web plates. If, as is usually the case, the system of flange stresses is somewhat unbalanced (i. e. out of equilibrium), then the system of web stresses must be unbalanced the same amount in the opposite direction. Shearing reactions between flanges and adjoining webs within the joint result from the unbalance and the flange system and web system are therefore not completely independent, there being minor adjustments. However, the basic principle of the joint of the truss structure of the present invention is that the flange stresses and the web stresses are separately transmitted through the joint by substantially independent means, capable of developing the full strength of each component part or as much thereof as may be necessary.

The diaphragm means which accomplishes this desired end of course may comprise diaphragm plates such as 141, 144 and 146 of Figs. 8, 9 and 10, or a solid block of material which substantially encompasses the lines of action, such as the element 60 proposed in Fig. 12. Any piece or pieces of material capable of transmitting from each corner to the other two corners of the triangular pattern the stress components in those two directions caused by the two flange stresses acting on the corner first mentioned may be employed within the scope of the invention.

It will thus be seen from Figs. 8 to 12 inclusive that the principles of the present invention may be incorporated in a joint of a truss side frame where two or more truss members of box formation are brought to junction by providing diaphragm means to constitute a truss system of triangular pattern or its equivalent. The joint may be an end junction of two box-section members suitably associated with support means for stress transfer as proposed in connection with Fig. 7 or a junction of three or more box-section members as proposed in Figs. 8 to 12 inclusive. The joint of Fig. 7, or its equivalent, and that of Figs. 8 and 12 require diaphragm means providing a single triangular stress transmitting means connecting all of the flange plates or transverse elements together including all junctures thereof. A larger number of box-section members can be joined according to the same principle by adding diaphragm means, such as two additional diaphragm plates or their equivalent for each additional member, the requirement being that the system of diaphragm means provide triangles of stress transfer or equivalents, one such triangle for the first three members or the joint of Fig. 7 and one additional such triangle for each additional member.

It will thus be seen that the objects set forth above are efficiently attained and since certain changes may be made in the above construction and different embodiments of the invention could be made without departing from the scope

thereof, it is intended that all matter contained in the above description or shown in the accompanying drawings shall be interpreted as illustrative and not in a limiting sense.

5 It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A truss side frame comprising, in combination, a pair of wheel connecting means, a longitudinal compression member joined to said wheel connecting means, a tension member including a bolster spring seat section and a pair of flanking oblique sections each joined to said compression member and to said wheel connecting means, each of said members being of box formation comprising a pair of flange plates and a pair of web plates, said flange plates being joined together along transverse lines of meeting to provide a plurality of junctures, and diaphragm means at each of the junctions of said members joined along transverse lines of meeting to all of the junctures and to any remaining flange plates which have no transverse lines of meeting with other flange plates and providing substantially direct rigid connections between all of said flange plates by the equivalent of a truss system of triangular pattern.

2. A truss side frame comprising, in combination, a pair of wheel connecting means, a longitudinal compression member joined to said wheel connecting means, a tension member including a bolster spring seat section and a pair of flanking oblique sections each joined to said compression member and to said wheel connecting means, each of said members being of box formation comprising a pair of flange plates and a pair of web plates, said flange plates being joined together along transverse lines of meeting to provide a plurality of junctures, and diaphragm plates at each of the junctions of said members joined along transverse lines of meeting to all of the junctures and to any remaining flange plates which have no transverse lines of meeting with other flange plates and providing substantially direct rigid connections between all of said flange plates by a truss system of triangular pattern.

3. A truss side frame comprising, in combination, a pair of wheel connecting means, a longitudinal compression member joined to said wheel connecting means, a tension member including a bolster spring seat section and a pair of flanking oblique sections each joined to said compression member and to said wheel connecting means, a pair of substantially vertical bolster guide column members each joined at one end thereof to said compression member and at its other end to said tension member in the vicinity of the junction of said seat section with one of said oblique sections, each of said members being of box formation comprising a pair of flange plates and a pair of web plates, said flange plates being joined together at the junctions of said compression and tension members and said column and tension members along transverse lines of meeting to provide a plurality of junctures, and diaphragm means at each of those junctions joined along transverse lines of meeting to all of the junctures and to any remaining flange plates which have no transverse lines of meeting with

other flange plates and providing substantially direct rigid connections between all of said flange plates by the equivalent of a truss system of triangular pattern.

4. A truss side frame comprising, in combination, a pair of wheel connecting means, a longitudinal compression member joined to said wheel connecting means, a tension member including a bolster spring seat section and a pair of flanking oblique sections each joined to said compression member and to said wheel connecting means, a pair of substantially vertical bolster guide column members each joined at one end thereof to said compression member and at its other end to said tension member in the vicinity of the junction of said seat section with one of said oblique sections, each of said members being of box formation comprising a pair of flange plates and a pair of web plates, said flange plates being joined together at the junctions of said compression and tension members and said column and tension members along transverse lines of meeting to provide a plurality of junctures, and diaphragm plates at each of those junctions joined along transverse lines of meeting to all of the junctures and to any remaining flange plates which have no transverse lines of meeting with other flange plates and providing substantially direct rigid connections between all of said flange plates by a truss system of triangular pattern.

5. A truss side frame comprising, in combination, a pair of wheel connecting means, a longitudinal compression member joined to said wheel connecting means, a tension member including a bolster spring seat section and a pair of flanking oblique sections each joined to said compression member and to said wheel connecting means, each of said members being of box formation comprising a pair of flange plates and a pair of web plates joined together, said flange plates being joined together along transverse lines of meeting to provide a plurality of junctures, and diaphragm means forming the equivalent of a triangular truss system at each of the junctions of said members located internally thereof between opposed web plates providing substantially direct connections between all of the flange plates at each of said junctions.

6. A truss side frame comprising, in combination, a pair of wheel connecting means, a longitudinal compression member welded to said wheel connecting means, a tension member including a bolster spring seat section and a pair of flanking oblique sections each welded to said compression member and to said wheel connecting means, each of said members being of box formation comprising a pair of flange plates and a pair of web plates joined together with at least some of the junctures being formed by welding, and diaphragm plates forming a triangular truss system at each of the junctions of said members located internally thereof between opposed web plates and welded in positions substantially to form continuations of interior flange plates extending to juncture with exterior flange plates.

7. A truss side frame comprising, in combination, a pair of wheel connecting means, a longitudinal compression member joined to said wheel connecting means, a tension member including a bolster spring seat section and a pair of flanking oblique sections each joined to said compression member and to said wheel connecting means, a pair of substantially vertical bolster guide column members each joined at one end thereof to said compression member and at its

other end to said tension member at the junction of said seat section with one of said oblique sections, each of said members being of box formation comprising a pair of flange plates and a pair of web plates joined together, said flange plates of the different members being joined together at the junctures thereof, and diaphragm means forming the equivalent of a triangular truss system at each of the junctions of said tension member with said compression and column members located internally thereof between opposed web plates providing substantially direct connections between all of the flange plates at each of said junctions.

8. A truss side frame comprising, in combination, a pair of wheel connecting means, a longitudinal compression member welded to said wheel connecting means, a tension member including a bolster spring seat section and a pair of flanking oblique sections each welded to said compression member and to said wheel connecting means, a pair of substantially vertical bolster guide column members each welded at one end thereof to said compression member and at its other end to said main tension member at the junction of said seat section with one of said oblique sections, each of said members being of box formation comprising a pair of flange plates and a pair of web plates joined together with at least some of the junctures being formed by welding, and diaphragm plates forming a triangular truss system at each of the junctions of said tension member with said compression and column members located internally thereof between opposed web plates and welded in positions substantially to form continuations of interior flange plates extending to juncture with exterior flange plates.

9. A truss side frame comprising, in combination, a pair of wheel connecting means, a longitudinal compression member welded to said wheel connecting means, a tension member including a bolster spring seat section and a pair of flanking oblique sections each welded to said compression member and to said wheel connecting means, a pair of substantially vertical bolster guide column members each welded at one end thereof to said compression member and at its other end to said tension member at the junction of said seat section with one of said oblique sections, each of said members being of box formation comprising a pair of flange plates and a pair of web plates joined together with at least some of the junctures being formed by welding, and diaphragm plates forming a triangular truss system at each of the junctions of said tension member with said compression and column members located internally thereof between opposed web plates and welded in positions substantially to form continuations of interior flange plates extending to juncture with exterior flange plates, one of the flange plates of each of said column members being joined to the interior flange plates of said seat section and adjacent oblique section at their juncture and one of said diaphragm plates being joined to and extending between said juncture of interior flange plates and the juncture of exterior flange plates of the seat and oblique sections with another one of said diaphragm plates being joined to exterior flange plates at the last-named juncture and extending to juncture with an interior flange plate of said tension member at juncture therewith of the other flange plate of said column member.

10. A truss side frame comprising, in combination, a pair of wheel connecting means, a longi-

tudinal compression member welded to said wheel connecting means, a tension member including a bolster spring seat section and a pair of flanking oblique sections each welded to said compression member and to said wheel connecting means, a pair of substantially vertical bolster guide column members each welded at one end thereof to said compression member and at its other end to said tension member at the junction of said seat section with one of said oblique sections, each of said members being of box formation comprising a pair of flange plates and a pair of web plates joined together with at least some of the junctures being formed by welding, and diaphragm plates forming a triangular truss system at each of the junctions of said tension member with said compression and column members located internally thereof between opposed web plates and welded in positions substantially to form continuations of interior flange plates extending to juncture with exterior flange plates, one of the flange plates of each of said column members being joined to the interior flange plates of said seat section and adjacent oblique section at their juncture and one of said diaphragm plates being joined to and extending between said juncture of interior flange plates and the juncture of exterior flange plates of the seat and oblique sections with another one of said diaphragm plates being joined to exterior flange plates at the last-named juncture and extending to juncture with the interior flange plate of said oblique section at juncture therewith of the other flange plate of said column member.

11. A truss side frame comprising, in combination, wheel connecting means at each end of the frame, a longitudinal compression member welded to each of and extending between said wheel connecting means, a tension member including a bolster spring seat section and a pair of flanking oblique sections each welded to said compression member and adjacent wheel connecting means, each of said members being of box formation comprising a pair of flange plates and a pair of web plates joined together with at least some of the junctures being formed by welding, diaphragm plates at each of the junctions of said members located internally thereof between opposed web plates and welded in positions substantially to form continuations of interior flange plates extending to juncture with exterior flange plates, the diaphragm plate which forms a continuation of the interior flange plate of the oblique section at either end of the frame being substantially aligned therewith and the exterior flange plate of said compression member terminating at either end substantially at the juncture with said last-mentioned diaphragm plate, and an additional pair of obliquely arranged diaphragm plates welded in position with each extending from one end of the exterior flange plate of said compression member to the juncture of the exterior flange plate of the oblique section with the diaphragm plate which forms a continuation of the interior flange plate of said compression member.

12. A truss side frame comprising, in combination, wheel connecting means at each end of the frame, a longitudinal compression member welded to each of and extending between said wheel connecting means, a tension member including a bolster spring seat section and a pair of flanking oblique sections each welded to said compression member and adjacent wheel con-

necting means, each of said members being of box formation comprising a pair of flange plates and a pair of web plates joined together with at least some of the junctures being formed by welding, diaphragm plates at each of the junctions of said members located internally thereof between opposed web plates and welded in positions substantially to form continuations of interior flange plates extending to juncture with exterior flange plates, the diaphragm plate which forms a continuation of the interior flange plate of the oblique section at either end of the frame being substantially aligned therewith and the exterior flange plate of said compression member terminating at either end substantially at the juncture with said last-mentioned diaphragm plate, and an additional pair of obliquely arranged diaphragm plates welded in position with each extending from one end of the exterior flange plate of said compression member to the juncture of the exterior flange plate of the oblique section with the diaphragm plate which forms a continuation of the interior flange plate of said compression member, each of said wheel connecting means comprising a substantially vertically arranged flange plate welded to the end of said frame substantially at the juncture of said obliquely arranged diaphragm plate with the exterior flange plate of said tension member and a pair of web plates joined to said vertically arranged flange plate and the oblique section of said tension member.

13. A truss side frame comprising, in combination, wheel connecting means at each end of the frame, a longitudinal compression member welded to each of and extending between said wheel connecting means, a tension member including a bolster spring seat section and a pair of flanking oblique sections each welded to said compression member and adjacent wheel connecting means, each of said members being of box formation comprising a pair of flange plates and a pair of web plates joined together with at least some of the junctures being formed by welding, diaphragm plates at each of the junctions of said members located internally thereof between opposed web plates and welded in positions substantially to form continuations of interior flange plates extending to juncture with exterior flange plates, the diaphragm plate which forms a continuation of the interior flange plate of the oblique section at either end of the frame being substantially aligned therewith and the exterior flange plate of said compression member terminating at either end substantially at the juncture with said last-mentioned diaphragm plate, and an additional pair of obliquely arranged diaphragm plates welded in position with each extending from one end of the exterior flange plate of said compression member to the juncture of the exterior flange plate of the oblique section with the diaphragm plate which forms a continuation of the interior flange plate of said compression member; each of said wheel connecting means comprising a support joined on its inner side to the exterior flange plate of the oblique section of said tension member, a substantially vertically arranged flange plate joined to said support and to the end of said frame substantially at the juncture of said obliquely arranged diaphragm plate with said exterior flange plate of said tension member, and a pair of web plates joined to said support, to said vertically arranged flange plate and to the web

plates of the oblique section of said tension member and aligned with the latter.

GILBERT D. FISH.
